SIPHONING DEVICE

Hugh Stephens, East Kildonan,
Manitoba, Canada

Application June 8, 1946, Serial No. 675,464

4 Claims. (Cl. 137—147)

1

One of the arduous tasks confronting the housewife today is that of emptying tubs and such like containers on washdays. Faced with this problem she proceeds to bale out the water with a dipper or similar object until the volume of water is reduced to the point where the tub can be handled bodily.

This applies with equal emphasis to the handling of all liquids including acids in quantity in factories, etc., where the corroding effect of acids on metals in many cases obviates the use of drain pipe fittings with tanks.

The principal object of my invention is to provide a simple labor saving device, designed to simplify the task of emptying liquids from a container normally too heavy and cumbersome to be handled physically.

A second object of my invention is to provide a siphoning device by which with a minimum of effort and inconvenience, a siphon flow of liquid will be induced and once induced, maintained until the container is drained.

Another object of my invention is to provide a siphoning device which is designed to maintain a partial vacuum within the siphoning vessel in order that it shall adhere to the floor of the container while in operation.

A further object of my invention is to include the use of a common faucet connection in order that the device may be used for filling a container with liquid.

An additional object of my invention is to provide a siphoning device which can be molded, coupled with standard components and fittings and thus be relatively cheap to manufacture.

With the above important and other minor objects in view which will become more apparent as the description proceeds, the invention consists essentially in the construction and arrangement of parts hereinafter more particularly described reference being had to the accompanying drawings in which:

Figure 1 is a partial vertical section through a wash tub, showing the invention in operating position and in vertical section.

Figure 2 is an enlarged inverted plan view of the suction cup.

Figure 3 is an enlarged vertical section of the suction cup showing the flap intake valve.

Figure 4 is a partial vertical section through a wash tub, showing an alternative embodiment of the invention in operating position and in vertical section.

Figure 5 is an enlarged inverted plan view of the suction cup in the alternative embodiment.

2

Figure 6 is an enlarged inverted isometrical view of the valve detail of the alternative embodiment.

In the drawing, like characters of reference indicate corresponding parts in the several figures.

A metal wash tub or tank 1 is generally indicated in Figure 1 partially filled with liquid such as water 2. The invention consists of a conduit 3 connected to a vessel 4 of variable interior capacity, which is positioned on the floor of the said tank. This vessel 4 consists of a hollow, relatively hemispherical casing, formed of rubber or similar material and of a shape resembling the well known plumber's force cup and which can be collapsed in the same manner. For simplicity this vessel will hereinafter be referred to as a suction cup or priming cup.

The upper portion of the suction cup 4 is provided with a nub or boss 5 with an opening therethrough to receive the end of a conduit or tubing 3 rigid or flexible, to which it is fastened as by cementing or vulcanizing.

The lip 6 of the suction cup 4 is provided with a flared flange 7 extending inwardly and downwardly over the entire circumference for the purpose of preventing the expulsion of liquid past the lip 6 when external pressure is applied to the suction cup 4.

To control the flow of liquid, a one way flap valve is provided by means of a rectangular opening 8 in the wall of the suction or priming cup 4 covered on the inside by a rectangular sheet 9 of the same material as the suction cup 4 and with the upper edge of the said sheet fastened to the inside of the cup 4 as by cementing or vulcanizing. This rectangular sheet 9 hinges on said vulcanizing to form a flap over the opening 8 so that pressure from the outside will cause it to open and pressure from the inside will cause it to shut tight.

With the tub or tank partially filled with water as in Figure 1, the suction or priming cup 4 is placed on the floor of the tank with the tube or conduit 3 overhanging the edge thereof and extending therebelow. External pressure is then applied to the priming or suction cup 4 initially flattening the inner flared flange 7 against the floor of the tank thus sealing off from the tank 1 the liquid within the cup 4. Additional pressure collapses the said cup forcing the liquid trapped within it to flow through the tubing 3 thus priming the siphon. Then by releasing the pressure, the cup 4 returns to its normal shape causing a partial vacuum therein. This reduction of pressure within the cup 4 coupled

with hydraulic pressure from the fluid body surrounding the cup causes the one way valve 9 to open permitting a continuity of flow of the liquid from the tank 1 through the opening 8 until the said tank is drained.

It is possible for the siphon flow, once induced, to activate a sufficiently sensitive valve and thus perpetuate the flow without the necessity of the cup or vessel returning to its original shape.

In the case of the alternative embodiment, the form of the inlet valve opening 8 with its complementary valve 9 shown in Figures 1, 2, and 3, is replaced by a number of grooves 13 in the face of the lip 6 of the cup 4, said grooves being covered by thin flap valves 14, hinged to the inside of said cup.

This alternative valve design which has the advantage of draining the tank to a lower level is shown in Figures 4 and 5 and enlarged and in greater detail in the inverted view in Figure 6 from which it will be seen that when viewed from the interior of the cup, the valves have the appearance of hollow buttresses 21 to the interior of the wall of the cup 4. These buttresses are formed by the front wall 14 and side walls 16.

The principle by which the alternative valve operates is the same as in the original design but differs in construction. Manufacturing technique requires that the buttress-like valve assemblies be moulded in one piece with the cup. When an incision 22 is made, as with a sharp knife, in both side walls 16 of the buttress 21 at a point immediately behind the front wall 14, and running parallel to the inclination of the wall, said front wall hinges to create a one-way flap valve and wall opening. This incision extends beyond the roof of the groove 13 in order to give greater freedom for the valve to swing clear, thus making an unobstructed passage for the entrance of liquid into the cup 4 via the groove 13.

Extending grooves 13 beyond the inner side of the wall of the cup so as to form hollow buttresses performs the threefold object (one) of facilitating the incision operation, (two) of avoiding cutting the major flared flange 20 which would reduce its effectiveness and (three) since the wall of the cup is subject to a vertical load at the moment of valve opening, the slope of the wall permits the valve to swing without binding on the floor of the tank 1.

The existence of a minor flared flange 15 at the bottom of the hinged wall or flap valve 14 serves the double purpose that when an increase of pressure develops within the cup 4 as a result of the collapsing action, the valve 14 is stiffened by the minor flared flange 15 against horizontal distention and is thereby prevented from protruding into the groove 13. At the same time this pressure bears down on the minor flared flange 15 to seal it against the floor of the tank, thus preventing the escape of liquid at this point.

A faucet connection 12 is shown secured to the free end of the conduit or tubing 3 and I desire its use in association with my device for the purpose of filling a container with liquid.

In general design, in order to achieve the full priming action with one downward stroke, the normal volumetric displacement of the priming and suction cup 4 should exceed the interior volume of the tubing 3 from the surface level of the liquid in the tank 1 to a point remote from said tank and sufficiently below the surface level of the said tank to create a head.

A holdown suction force becomes evident

when the area of the inlet valve opening 8 in the cup 4 is less than the outlet 11. It has been found by experiment that discounting the influence of head, which is a variable factor, this holdown force in terms of atmospheric pressure is approximately proportionate to the difference in the relative areas of the inlet and outlet openings.

Since the area of the outlet 11 coupled with the head of water largely determines the extent of the flow, it will be seen that any increase in the holdown force caused by restricting the inlet opening 8 or the sum of the openings 13 is only obtained at the expense of the outflow.

It is desirable and advisable therefore that the cross-sectional area of the outlet 11 shall exceed that of the inlet openings 8 and 13 by only such margin as will assure the adherence of the suction cup 4 to the floor of the tank 1 throughout the whole of the drainage operation.

The need for a siphoning device to adhere to the floor of the tank 1 is not indispensable, but the omission of this factor in the design would cause cup 4 to float and in giving elevation to the valve would impair its efficiency by only partially draining the said tank.

The two embodiments shown are illustrative of a means of priming for a siphon flow of liquid and the timely and continuing means of insuring the admission of fluid into the siphoning assembly. Such embodiments are amenable to many structural modifications without departing from the principle involved and I desire only such limitation as is placed upon them by the scope of the appended claims.

What I claim as my invention is:

1. A siphoning assembly comprising in combination a flexibly deformable vessel having an open end, said open end having an annular flexible lip, said flexible lip so constructed as to be capable of sealably engaging a fluid submerged surface, a conduit connected to and communicating with the interior of said vessel, valved inlet means on said vessel preventing egress of fluid from said vessel into the surrounding fluid body but permitting flow in the reverse direction.

2. A siphon initiated solely by hydraulic action comprising in combination a flexibly deformable vessel open at one end and so constructed that said open end be capable of sealably engaging the bottom of a container from which liquid is being siphoned, a conduit connected to and communicating with the interior of said vessel and a one way valve on said vessel automatically openable inwardly by a vacuum pressure differential as between the interior and exterior of said vessel.

3. A siphoning assembly comprising in combination a flexibly deformable vessel having an open end, said open end so constructed as to be capable of sealably engaging the bottom of a container from which fluid is being siphoned and valved inlet means on said vessel so arranged as to prevent egress of fluid from said vessel into the fluid body but permitting flow in the reverse direction, a conduit connected to and communicating with the interior of said vessel, the opening on said conduit being greater in cross-sectional area than the area of said inlet means.

4. A siphoning assembly retentive against a fluid submerged surface, comprising in combination a flexibly deformable vessel open at one end, said open end so constructed as to be capable of sealably engaging the bottom of a container from

which liquid is being siphoned, a conduit connected to and communicating with the interior of said vessel, a valved inlet means on said vessel permitting only ingress of fluid therein, said valved inlet means being less in area than said conduit opening, thereby securing said vessel 5 tentively to a fluid submerged surface during the siphoning operation.

HUGH STEPHENS.
